CLAIM

The ornamental design for a wall mounted status indicator, as shown and described.

DESCRIPTION

FIG. 1 illustrates a top-right perspective view of a wall mounted status indicator.

FIG. 2 illustrates bottom-left perspective view of a wall mounted status indicator.

FIG. 3 illustrates a front elevation view of a wall mounted status indicator.

FIG. 4 illustrates a right elevation view of a wall mounted status indicator.

FIG. 5 illustrates a left elevation view of a wall mounted status indicator.

FIG. 6 illustrates a top plan view of a wall mounted status indicator; and,

FIG. 7 illustrates a bottom plan view of a wall mounted status indicator.

The broken lines illustrate portions of the wall mounted status indicator that form no part of the claimed design.

1 Claim, 6 Drawing Sheets
